UNITED STATES PATENT OFFICE.

JOHN H. LAWLESS, OF JERSEY CITY, NEW JERSEY.

SELF-ACTING SUPPLY-TANK.

SPECIFICATION forming part of Letters Patent No. 601,474, dated March 29, 1898.

Application filed December 15, 1897. Serial No. 661,955. (No model.)

To all whom it may concern:

Be it known that I, JOHN H. LAWLESS, a citizen of the United States, residing at Jersey City, in the county of Hudson and State 5 of New Jersey, have invented certain new and useful Improvements in Self-Acting Supply-Tanks, of which the following is a specification.

This invention relates to an improved self-10 acting supply-tank which is intended for the upper floors of tenement-houses, factories, and other high buildings, so that a sufficient quantity of water can be supplied automatically to all the different floors of the building 15 without the use of special pumping apparatus. A self-acting supply-tank of similar construction was heretofore patented by me, No. 338,984, on March 30, 1886; but it was found by practical tests that said supply-tank 20 was operative only in case a high water-pressure was sustained in the main supply-pipe, but that with a lower pressure of water in the same the apparatus could not perform the work of lifting the water to the different 25 floors of the building. As in most water-supply systems the water-pressure is not sufficient to produce the pressure required for the proper working of my tank, it could not be successfully introduced into general use.

30 The object of the present invention therefore is to furnish a self-acting supply-tank which is located at the top of a building and by which a sufficient flow of water is supplied in an absolutely reliable and effective manner whenever required and in which the drawing off of the water from the tank assists in raising the water from the main to the supply-tank; and the invention consists of a hermetically-closed supply-tank that is provided 35 with a supply-pipe of inverted-U shape, extending through the bottom to within a short distance from the top of the tank and down again to a point near the bottom, a discharge-pipe connecting the bottom of the tank with the service-pipes, the supply and discharge 40 pipes being provided with stop-cocks for cutting out the tank, if necessary, or disconnecting the tank from the supply and discharge pipes when required.

45 In the accompanying drawings, Figure 1 represents a vertical section through a building, showing my improved self-acting sup-

ply-tank at the top floor of the same and connected with supply and service pipes. Fig. 2 is a vertical transverse section through the 55 tank, drawn on a larger scale; and Fig. 3 is a vertical section through the supply and service pipes, showing the discharge and supply pipes connected with the bottom of the tank, drawn on a larger scale. 60

Similar letters of reference indicate corresponding parts.

Referring to the drawings, A represents a hermetically-closed supply-tank, which is preferably made of cylindrical shape, having 65 a dome-shaped top, and of a size proportioned to the quantity of water required. The supply-tank A is made of sheet metal of suitable strength and is located at the top of the building at such a height that different sizes of basins, &c., can be supplied from the same. 70

The tank A is connected by means of a supply-pipe B with a main m, said supply-pipe passing through the bottom of the tank to a point at some distance from the top of the 75 same and in downward direction back to a point at some distance from the bottom, forming an inverted-U-shaped supply-pipe. The supply-pipe is inserted into the interior of the tank through a discharge-pipe C, which 80 is of sufficient diameter to permit the free introduction thereof. The discharge-pipe C is attached to the bottom of the tank and surrounds the supply-pipe B and is suitably connected with the service-pipe D, by which the 85 apartments in the different stories of the building are supplied with water.

The supply-pipe B and service-pipe D are provided below the tank with stop-cocks d d', by which the supply-tank can be disconnected 90 from the supply and discharge pipes when it is necessary to clean or repair the same. The stop-cocks are provided with vents e e', as shown in Fig. 3, for permitting the venting of the tanks and service-pipes when the same 95 are to be emptied for repairs.

My improved self-acting supply-tank operates as follows: The water is supplied to the tank until the same is filled nearly to the top. The air is compressed at the dome-shaped top 100 and is gradually absorbed in the water, whereby the air-chamber is gradually reduced until the tank is almost entirely filled. As soon as the water is drawn off through any

one of the faucets of the service-pipe a partial vacuum is created in the upper part of the tank, which assists in lifting the water from the main and supply pipes to the tank as fast as it is drawn off. Owing to the inverted-U shape of the supply-pipe this vacuum cannot be destroyed unless the water falls below the lower end of the supply-pipe, which cannot occur during the regular working of the tank.

10 The suction of the vacuum in the tank, in connection with the pressure in the main, is sufficient to keep the tank always full of water, so as to supply the required quantity to the service-pipes. When it is desired to cut out 15 the service-pipes for any reason, the stop-cocks d d' are closed. This opens the vent e of the same, and air is thereby supplied to the interior of the tank, which permits the emptying of the same. Simultaneously the 20 air is supplied to the upper end of the service-pipes, so that they can be entirely emptied. A number of faucets may be opened at the same time and deliver any desired quantity of water, as the tank will be able to supply all the water required.

25 My improved self-acting supply-tank is intended for use in place of ordinary tanks located at the top of buildings and has the advantage that it takes up less room and is not liable to get out of order owing to the uncertain working of the float-valves or from leakage, &c. The tank is supported on a standard of suitable height and is secured by a pin p at its top to the ceiling, so as to be firmly held in position.

30 The supply-tank forms a valuable auxiliary

35 to water-supply systems in which the pressure in the mains is not sufficient to supply the required quantity of water, and it is particularly adapted for use in dwellings and small factories, in which a pumping arrangement for water would be objectionable, owing to its expense and inconvenience.

40 Having thus described my invention, I claim as new and desire to secure by Letters Patent—

45 1. A hermetically-closed water-supply tank, provided with a supply-pipe of inverted-U shape passing through the bottom of the tank to a point near the top of the same and downward to a point near the bottom of the same, and a discharge-pipe at the bottom of said tank, said supply-pipe being connected with the main, substantially as set forth.

50 2. The combination of a hermetically-closed supply-tank, a supply-pipe extending through the bottom of the tank, to the top thereof and downward to a point near the bottom of the tank, a pipe connecting said supply-pipe with the main, a discharge-pipe in the bottom of the tank connected with the service-pipe, and stop-cocks having vent devices located below the tank in the supply and discharge pipes, substantially as set forth.

55 In testimony that I claim the foregoing as my invention I have signed my name in presence of two subscribing witnesses.

JOHN H. LAWLESS.
